OTHER PUBLICATIONS Cuisipro Egg Poacher; www.cooking.cuisipro.com; 1 page; published as of the filing date of this application, Feb. 15, 2011.*Primary Examiner* — Ricky Pham(74) *Attorney, Agent, or Firm* — Lempia Summerfield Katz LLC**(57) CLAIM**

The ornamental design for an "egg poacher," as shown and described.

DESCRIPTION

FIG. 1 is a top, front, and right side perspective view of our new design for an egg poacher.

FIG. 2 is a front view of the egg poacher shown in FIG. 1.

FIG. 3 is a rear view of the egg poacher shown in FIG. 1.

FIG. 4 is a right side view of the egg poacher shown in FIG. 1, the left side view being a mirror image thereof.

FIG. 5 is a top view of the egg poacher shown in FIG. 1; and, FIG. 6 is a bottom view of the egg poacher shown in FIG. 1. The subject matter shown in dashed lines is for illustrative purposes and forms no part of the claimed design.
